UNITED STATES PATENT OFFICE.

ALDEN L. HOWARD, OF ANN ARBOR, MICHIGAN.

PHONOGRAPH.

1,369,280.

Specification of Letters Patent. Patented Feb. 22, 1921.

Application filed April 22, 1920. Serial No. 375,686.

To all whom it may concern:

Be it known that I, ALDEN L. HOWARD, a citizen of the United States, residing in the city of Ann Arbor, county of Washtenaw, 5 and State of Michigan, have invented certain new and useful Improvements in Phonographs, of which the following is a specification.

My invention relates to improvements in 10 phonographs and relates more particularly to a starting and stopping device for phonographs using the disk type record.

Among its salient objects are to provide a device or attachment which automatically 15 starts the record disk to rotating when the reproduction horn is in position for the needle to be placed upon the record, and automatically stops the record disk when the record has been completed; to provide 20 a device that is adapted to be mounted on any type of disk machine, one that is positive in its operation, simple in construction, besides having the working parts conveniently positioned for adjustment; to provide 25 a device that may be permanently adjusted due to the fact that there is practically no wear upon the actuating mechanism; to provide an attachment that is quickly detachable from the machine by removing a 30 single plate upon which the exposed mechanism is mounted and in general to provide a device of the character hereafter referred to.

In the drawings:

35 Figure 1 is a fragmentary edge view of the mechanism of a disk type phonograph with parts broken away and parts shown in section.

Fig. 2 is a plan view of substantially that 40 part of the mechanism shown in Fig. 1.

Fig. 3 is a detail view taken on line 3—3 of Fig. 2, looking in the direction of the arrow.

Fig. 4 is a detail view of the pinion which 45 meshes with the rack shown in Fig. 2.

Referring to the drawings, only that part of the mechanism of a disk type phonograph is shown as is particularly related to the automatic starting and stopping device.

50 Two large springs shown at 1 furnish power for the driving motor. These springs together with the large helical gear 2 are mounted upon a shaft 3, which is carried by suitable bearings 4. These bearings are part 55 of a frame 5, which is fixedly attached to the upper table portion 6. The disk 7 which

carries the record 8 is rotated by means of a vertical shaft 9 upon which is cut a worm 10, which meshes with the helical gear 2. The speed of the shaft and the disk is regulated by means of a governor (not shown) driven through the gear 11 and worm 12. A helical gear 13, which meshes with the larger gear 2 of a similar character, is mounted in shaft 14, the latter being also 60 carried by the frame 5. To this shaft 14 is also fixed a worm 15, which drives a horizontally positioned gear 16. The gear 16 is mounted on a vertical shaft 17 to which is also rotatably mounted on the top thereof 65 a pinion 18. The top of the vertical shaft 17 is slotted as shown at 19 and in this slot is placed a light flat friction spring which is held in place by means of the nut 20. This spring is slightly bowed and either end 70 slightly twisted longitudinally in opposite directions so that with the setting up of the nut, the ends of the spring will frictionally contact the top of the pinion 18 when it is rotated in a counterclockwise direction 75 and turn freely when rotating in a clockwise manner. The friction caused by this spring is hardly perceptible but it is sufficient to positively actuate the mechanism. The pinion 18 meshes with a rack 21, which is an 80 integral part of the member sliding in the central slot 22 of the arc 23. The arc upon which the rack is cut is centered at 24, as is the reproducing arm 25, which is connected to the sounding box 26 by means of a curved 85 tube connection 27. This curved tube may be rotated so as to raise and lower the sounding box and needle 28 from contact with the record. The arc 23 on the other hand, in which is slidably mounted the rack 21 is 90 centered at 29. This arc is pivoted at 30 and a rotative tension in the direction of the arrow is constantly held upon the arc by means of the coil spring 31.

Adjustably fixed by means of the set 100 screws 32, to the top of the rack member 21 and sliding with it in the slot 22, is a plate member 33. In this plate member is cut an L-shaped slot 34 and into the shorter portion of this slot is screwed a set screw 35, which 105 is adapted to regulate the length of the slotted portion or more properly, the width of the shoulder upon which the vertical pin 36 may rest. This vertical pin is riveted to the sound tube 25 as shown in Fig. 1. The 110 lower portion of this pin or that portion which rests upon the shoulder of the L-slot

is squared so that its dropping from the shoulder into the longer portion of the slot is instantaneous.

The mechanism is simply mounted upon 5 the top surface of any disk machine as the plate 37 is fitted beneath the flange 38 of the sound arm and is held in place by the screws 39. This plate fixes the center 24 for the rack and has upon its surface a hole in 10 which is set the pivot screw 30 for the arc 23. An extended portion 37a of the plate 37 is apertured to fit over the sleeve bearing 17a as shown in Fig. 4. In this manner, besides fixing the centers of the rack and 15 eccentrically arranged arc, the center of the pinion 18, by means of the expansion of the plate, is set relative therewith. At the end of the arc 23 is fixedly attached a narrow plate 40, upon which is fixed the leather or rubber stop 41. This stop is adapted to 20 contact the inner circumference of the disk 7 and prevent its rotation.

The operation of the device is as follows: When the sound tube 25, together with the 25 sound box 26, are rotated upon their pivot 24 to place the needle upon the outer edge of the record in beginning a selection, the pin 36 will drop into the longer portion of the slot 34, due to the eccentric arrangement 30 of the arc 23, and the tension held upon the arc by means of the coil spring 31. As the tube is moved to the outer edge of the record, the rack and plate member 33 slide in the slot 22, drawing the arc 23, toward the 35 disk 7 against the tension of the spring 31. The moving of this arc toward the disk will draw the stop 41 from contact with the disk and automatically release the disk so that it may rotate. At this time, the rack will be 40 out of mesh with the pinion 18. As the needle moves horizontally across the face of the record, the rack and pinion will mesh and as the pinion 18 is geared from the motor to rotate in timed relation with the 45 travel of the needle across the record, the movement of the rack and pinion is practically identical. To allow for any difference in the movement of these two members, I have frictionally mounted the pinion as 50 previously explained. With the starting of the disk, the pin 36 is positioned upon the shoulder of the slot 34 as is shown in Fig. 2, and remains in this position until the needle has advanced to the end of the 55 selection. At this time, the sound arm will become stationary as the needle is riding continuously in an endless groove in the record. The pinion, however, which is driven from the motor, continues to rotate and meshing 60 with the rack causes it to move as before. The continued movement of the rack causes the pin to drop from the shoulder of the L-slot, thereby permitting the coil spring 31 to take effect and throw the stop 41 in contact with the edge of the disk. The length 65

of time which the disk and record are allowed to rotate after the completion of the selection may be regulated by restricting the size of the shoulder upon which the pin 36 rests by means of the set screw 35.

70

It will be seen from this that by merely placing the sound box in position at the edge of the disk or record, the latter will immediately commence to rotate and will continue to rotate until the selection has been 75 completed or the needle has become stationary upon the record.

75

I claim as my invention:

1. In an automatic starting and stopping device, for phonographs, the combination 80 with a rotating disk and reproducing mechanism adapted to progress horizontally across substantially one half of the disk during its rotating period, of an automatically actuated arc adapted to frictionally contact the disk, operative connections between the reproducing mechanism and the arc for automatically starting and stopping the rotation of the disk.

85

2. In an automatic starting and stopping 90 device, for phonographs, the combination with a rotating disk and reproducing mechanism adapted to ride horizontally across substantially one half of the disk during its rotating period, of an automatically actuated 95 arc adapted to frictionally contact the disk, operative between the reproducing mechanism and the arc operating to start the disk when the reproducing mechanism is in position near the circumference of the 100 disk, and to stop the disk when the reproducing mechanism is positioned near the center of the disk.

95

3. In a starting and stopping device for 105 phonographs, the combination with a rotating disk, of a reproducing mechanism adapted to move horizontally across substantially one half of the disk during the rotating period, an automatically actuated arc eccentrically positioned with reference to said 110 reproducing mechanism and adapted to frictionally contact the disk, operative connections between the reproducing mechanism and the arc, for automatically starting and stopping the rotation of the disk.

115

4. In a starting and stopping device for 120 phonographs, the combination with a rotating disk, of a reproducing mechanism adapted to move horizontally across substantially the radius of the disk during the rotating period, an automatically actuated arc adapted to frictionally contact the rotating disk, having a sliding member therein, moving in timed relation with the reproducing mechanism, operative connections between 125 the sliding member of the arc and the reproducing mechanism for automatically starting and stopping the rotation of the disk.
